UNITED STATES PATENT OFFICE.

JOSEPH P. CONWAY, OF LOS ANGELES, CALIFORNIA.

TELEGRAPHIC TRANSMITTER.

SPECIFICATION forming part of Letters Patent No. 738,525, dated September 8, 1903.

Application filed August 15, 1902. Serial No. 119,814. (No model.)

To all whom it may concern:

Be it known that I, JOSEPH P. CONWAY, a citizen of the United States, residing at Los Angeles, in the county of Los Angeles and State of California, have invented new and useful Improvements in Telegraphic Transmitters, of which the following is a specification.

My invention relates to telegraphic transmitters for sending electric signals according to the Morse alphabet or any other predetermined electric signals; and the objects thereof are to provide a machine of simple construction and operation with which a person skilled in type-writing can send a telegram in the Morse alphabet much more quickly than the same can be sent by hand by the most skilful telegraph operator. I accomplish these objects by the mechanism 20 described herein and illustrated in the accompanying drawings, in which—

Figure 1 is a perspective view of my transmitter with a portion of the case removed for clearness of illustration. Fig. 2 is a detail 25 of construction. Fig. 3 is an isometric view of the depression-bar.

In the telegraph system now in use, especially when using the ordinary key in connection with the Morse sounder and sending 30 all signals entirely by hand, the operator is liable to make mistakes in the letter or word and to jumble the letters and words together in an indistinct manner. Again, it is impossible to send with any great speed, as there 35 is a maximum limit to sending by hand.

According to my invention a keyboard of any standard type-writer is used, together with connecting mechanism, so that as the key representing a certain letter is depressed 40 the Morse or other predetermined signal corresponding to that letter or character will be transmitted to the receiving-station. All the sending operator has to do is to press these keys consecutively to spell the word and send 45 the message, and he can send with as high a rapidity as it is possible to use the ordinary type-writer, each word and letter thereof being sent at a uniform speed. Since the make and break of the contact is done automatically and at a uniform rate, the work of the receiver will be much easier.

In my machine, A is the case, which incloses

the metallic key-levers B, which are provided with finger-buttons C, with characters thereon in the manner common to keyboards of type-writers. These key-levers are pivotally mounted on metallic rods D, which 55 longitudinally the case and transversely through partitions E, of non-conducting material, which extend transversely through the case, 60 separating the rows of keys from each other and providing suitable supports for the rods and for the stop-pins F. Wooden partitions I have found to be suitable. These rods are electrically connected by the metallic strip 65 G to the wire H of the telegraph-line. Rods L also run longitudinally the case and transversely through the partitions and are electrically connected together by the metallic strip I. These rods are connected to the 70 positive pole of battery J by strips I and wire M. The negative pole of the battery is electrically connected by wire K with the ground. On rods L are rigidly secured the metallic contact-springs N. These springs 75 are supported near their junction with the rods by supporting-pins O, driven in the partitions. On the bottom of the key-levers are formed contact-points or electric characters P to electrically produce the different letters of the Morse alphabet or other predetermined electric signals, the finger-button on the top being the representative of the electric character on the bottom of the lever. These key-levers are held normally 80 out of engagement with the contact-springs by retractile springs R, which also return the keys to their normal position after the key is depressed by the finger of the operator. Pivotally mounted on the same rods as the 85 key-levers are depressing-bars S, each of which has two arms S' and S'', which lie in the path of movement of the lower arm of the key-lever and are moved thereby, the extent of the movement being limited by the 90 stop-pins F. Normally the lower arm of the key-lever bears against the arm S' of the depressing-bar and holds it spring-pressed against a stop-pin. In this position the key-lever does not engage with the contact-spring. 95 When an operator desires to send a message, he strikes successively the finger-buttons which have the appropriate characters thereon which spell out the message. As the top 100

arm is depressed the lower arm of the key-lever is elevated and passes over the contact-spring, the points thereof engaging therewith, and thereby making and breaking the circuit in the same manner that the Morse key makes and breaks the circuit. The upward movement of the lower arm of the key-lever causes it to strike against the arm S' of the depression-bar and to carry it until its movement is arrested by the stop-pin F in its path. This movement of the depression-bar brings the central arm S'' into a position where it rests upon and holds contact-spring N depressed far enough that on the downward movement of the lower arm of the key-lever the contact-points thereof will not engage therewith. As soon as the operator releases the pressure on the upper arm of the key-lever the retraction-spring returns the lever to its normal position. In returning to its normal position the lower arm of the key-lever engages the arm S' of the depression-bar and carries the bar back to its normal position, thereby releasing the contact-spring, which then rises, so that the top thereof is in position to engage the contact-points on the lower arm of the key-lever whenever it is again moved upward. The depression-bar is made of any suitable non-conducting material. I have found fiber very satisfactory.

It will be seen that by the use of my machine all signals will be uniformly correct and even and that the speed with which a message can be sent is only limited by the speed with which an operator can operate the keys and that any person who can operate a type-writer can operate the machine and send telegraphic messages.

Having described my invention, what I claim as new, and desire to secure by Letters Patent, is—

1. In a telegraphic transmitter, a casing; a plurality of centrally-pivoted metallic levers mounted in said casing and electrically connected together, said levers having finger-buttons on the upper arms and contact-points on the lower arms thereof; said finger-buttons being provided with known characters on the top thereof, and said contact-points on the lower arm being the telegraphic representative of the top characters; a plurality of contact-springs electrically connected together and to the positive pole of a battery, the free ends of which said springs being

adapted to lie in the path of movement of the 55 said contact-points of the said key-levers; insulating pivoted depression-bars having arms on either side of the lower arm of said key-levers and lying in the path thereof and adapted to be moved thereby and a central 60 arm adapted to be moved to depress the contact-springs on the upward movement of the lower arm of said key-levers and to hold the same depressed until the passage thereover of said contact-points of said key-lever on 65 the downward movement of the lower arm thereof and then to be removed thereby from said contact-spring; a battery having the negative pole thereof electrically grounded.

2. In a telegraphic transmitter, a casing; 70 a plurality of pivoted key-levers mounted in said casing and electrically connected together, said levers having finger-buttons provided with known characters on the upper arm and contact-points on the lower arm, said 75 contact-points being the electrical representatives of the top characters; contact-springs electrically connected together having the tops thereof in the path of movement of the said contact-points of said key-levers, said 80 springs and levers being normally insulated from each other and adapted to contact on the upward movement of the lower arm of the said contact-lever; and means to move and retain the said contact-spring out of the path 85 of the said contact-points of said key-lever on the downward movement of the lower arm thereof.

3. In a telegraph transmitter, a casing; a contact-spring; a pivoted key-lever having 90 contact-points on the lower end thereof, adapted to engage said contact-spring on the upward movement of the lower end of said key-lever; an insulating depression-bar having arms adapted to lie on both sides of and 95 be moved upward and downward by said key-lever, a central arm adapted to be moved by said key-lever to remove and hold said contact-spring out of engagement with the contact-points of said key-lever on the downward 100 movement of the lower end thereof.

In witness that I claim the foregoing I have hereunto subscribed my name this 4th day of August, 1902.

JOS. P. CONWAY.
